UNITED STATES PATENT OFFICE.

JOHN G. JONES, OF ROCHESTER, NEW YORK, ASSIGNOR TO EASTMAN KODAK COMPANY,
OF ROCHESTER, NEW YORK, A CORPORATION OF NEW YORK.

ATTACHMENT FOR COATING-MACHINES.

1,312,034.

Specification of Letters Patent.

Patented Aug. 5, 1919.

Application filed July 23, 1917. Serial No. 182,121.

To all whom it may concern:

Be it known that I, JOHN G. JONES, of the city of Rochester, in the county of Monroe and State of New York, have invented 5 certain new and useful Improvements in Attachments for Coating-Machines; and I do hereby declare the following to be a full, clear, and exact description of the same, reference being had to the accompanying drawings, forming a part of this specification, and to the reference-numerals marked thereon.

My present invention relates to machines for coating webs of paper, or other material, with substances applied in liquid, or semi-liquid form, and it has for its object to provide means whereby the thickness of the coating may be very accurately gaged and uniformly applied. Generally stated the invention 15 comprises a rigid support having a face across which the web to be coated travels, and in front of this support is arranged a knife, or scraper, having provision for delicately adjusting it relatively to such supporting face whereby it regulates the thickness of the layer of coating material remaining on the web as it passes between the scraper and the support. The invention 20 also comprises an arrangement of parts whereby, when applying a comparatively thin coating layer to a web, particles of foreign matter, grit, or undissolved granules of coating material may slip, or pass beneath the coating gage, or knife. To these and 25 other ends the invention consists in certain improvements and combinations of parts all as will be hereinafter more fully described, the novel features being pointed out in the claims at the end of the specification.

40 In the drawings:

Figure 1 is a detail side elevation of a portion of a coating machine showing the general location and arrangement of the parts and mechanism comprising my present invention;

Fig. 2 is a top plan view thereof;

Fig. 3 is an enlarged view of a portion of Fig. 2;

Fig. 4 is a front elevation of the scraper;

50 Fig. 5 is a detail sectional view taken on the line 5^x—5^x of Fig. 3;

Fig. 6 is a similar view taken on the line 6^x—6^x of Fig. 3;

Fig. 7 is an enlarged detail view of the coöperating working portions of the web support and scraper.

Similar reference characters throughout the drawings indicate similar parts.

The mechanism embodying my present invention is adapted to coating machines used 60 for applying to a continuous ribbon, or web, of paper, fabric, or other sheet material, a coating of fluid, or semi-fluid material, which it is desired to spread evenly across the face of the web. The general arrangement of such machines is well known, and I have, therefore, only shown a portion of the forward end of a coating machine, comprising the coating roller 1, journaled on the frame 2 and rotating in a tray, or bath 3 65 containing the coating material which it conveys onto the web indicated by A. The latter, it will be understood, is drawn from a supply roll, located in rear of the coating roll, and after passing the latter and having the coating thus applied evenly distributed, or leveled, returns over one or more supporting rollers, and is finally wound 70 upon a rewinding arbor.

Devices embodying my invention coöperate with the web after the coating material has been applied and are supported upon forwardly extending brackets 4 at opposite sides of the machine. The precise position of the coöperating web support 85 and scraper with regard to the path of the web is not essential, but for convenience in operation and ease of inspection I prefer the general arrangement of parts shown in the drawings, comprising a guide roll 5 from 90 which the coated web passes upwardly into contact with the supporting surface, with which the scraper coöperates, from which the web is carried rearwardly, as shown particularly in Fig. 1. The supporting surface which engages the rear face of the web is preferably curved, and to this end is formed of a cylindrical bar 6, in the periphery of which one or more longitudinally extending grooves, or channels 7 are 95 cut, thus providing two parallel edges *a* and *b*, which are spaced to provide a short dis-

100

tance across the entire width of the web which is unsupported, thus allowing the web to yield laterally when necessary in a direction away from the scraper. The supporting edges of the slot, or channel, are, however, located sufficiently close to each other, depending upon the weight of the paper, fabric, or other material, so that as the latter is drawn across the face of the support it is held free and yet the formation of wrinkles, or cockles prevented. The surface of the bar adjacent the edges *a* and *b* of the slots 7 constitutes the working face of the support, and as this part is subject to wear it is desirable to provide several of the slots 7 and to support the bar at its ends in boxes 8, in which it may be rotated and clamped by set screws 9 with one or another of said slots in operative position. The web A in passing through the machine is under tension and it is, therefore, desirable that the bar be supported intermediate its ends, especially if the webs are comparatively wide. Therefore, I have provided a brace extending in rear of the bar 6 comprising parallel guides 10-10 attached at their ends to the boxes 8. Between the guides are cheek blocks 11, each containing a set screw 12 engaging a bearing block 13. The adjustment of the set screws 12 gives an added stability to the bar 6 to prevent it from bending rearwardly under the tension of the web across its forward face. Distortion of the bar, however, is not always due to the tension of the web and occasionally difficulty is experienced either as a result of thermal changes, or internal strains, due to machining operations, and for this reason I also provide means for moving the bar rearwardly as well as forwardly, by making the blocks 13 in the form of segmental collars, which are slipped over one end of the bar 6. In each of these collars is threaded a draw bolt 14 passing through the blocks 11. Thus it will be seen that the bar at one point may be thrust forward by a set screw 12 and at another point retracted by one of the bolts 14. This means of adjustment it will be seen provides great rigidity in the member forming the supporting surface of the web, which may be adjusted here and there throughout its length to bring the working face of said surface into a perfectly straight line. This arrangement of adjusting devices possesses a further advantage in that where it is desirable to apply a temperature controlling medium, such as steam, or cold water, to the supporting surface the bar 6 may be made hollow, as shown in Figs. 5 and 6, and suitable piping connections attached at each end, as indicated by 15, Fig. 2.

The coöperating element comprising the gage bar, or scraper, is preferably mounted at right angles to the supporting surface in

front of the groove 7, its point, or working edge, being preferably located midway between the edges *a* and *b* of said groove, but slightly beyond the plane common to said edges. It is not intended that the working edge of the scraper shall engage the outer face of the web, but rather that it shall be separated therefrom a distance represented by the thickness of the coating layer to be applied, and as this coating is usually measured in thousandths of an inch delicate micrometer adjusting devices are provided for the scraper.

In the preferred arrangement of these parts the support 16 is mounted in boxes 17 on the outer ends of the brackets 4, and in order that the support and the scraper carried thereon may always have a definite relationship to the bar 6, the boxes 8, in which the bar is carried, are secured rigidly to the support by means of the bolts 8^a. The upper face of the support 16 is flat and at each end is a sliding block 18 between which lies a scraper 19, pivoted to the blocks by pins 20, which permit it to rotate from its normal full line position to the dotted line position shown in Fig. 6. The blocks 20 are slotted and guided on pins 21 surrounded by bushings 22, which support cover plates 23. Beneath the latter is arranged a spring 24 in each of the blocks, which operates against the rear pin and the forward end of the slot, thus exerting a constant tendency on the scraper to move it toward the coöperating member, or web supporting surface. The exact position of the scraper is determined very accurately by two adjusting screws 25 extending transversely through the scraper bar 19 at its opposite ends. The outer ends of the screws are provided with knurled heads 26, provided with graduations coöperating with an index member, or pointer 27, and at their inner ends the screws rest against web supporting members, and where the latter is made in the form of a bar, it is provided with accurately turned annular grooves, or channels 28, which are cut slightly deeper than the longitudinally extending recesses, or grooves 7. By this arrangement of parts it will be seen that the adjusting screws engage the curved surfaces of the bottoms of the grooves 28 on the radii of the circles so that when it is desired to disengage the scraper it may be easily tilted upwardly by rotating it on the pins 20 and when it is again forced downwardly into operative position the ends of the screws 25 engage the cylindrical surfaces of the grooves 28, which act as cams to force the blocks 18 backward against the tension of their springs 24.

The rigidity of the scraper bar and its perfect alignment with the coöperating web supporting surface is assured by providing it with another overlying bar 29 bolted

thereto at its ends, as indicated at 30 in Fig. 3. This bar 29 is of sufficient dimensions and tensile strength in comparison with the bar 19 so that the latter may be deflected 5 transversely at the center by providing deflecting pressure screws 31 and 32, which engage opposite sides of the bar 29 and are carried in studs 33 and 34. Since the scraper is subject to wear and in certain 10 classes of work may require frequent sharpening, or renewal, I prefer to provide the bar 19 at its inner edge with a longitudinally extending groove in which is detachably secured a strip 35, the edge 35^a of which 15 may be formed as desired.

It is desirable in some classes of work that the temperature of the knife, or scraper, be maintained as nearly as possible to that of the web supporting surface with which it 20 coöperates, or in case the coating material which is applied to the web A be heated, that the scraper should be likewise heated and maintained at such a temperature that the coating material is not cooled when 25 brought into contact therewith. To this end the support 16 is provided with piping connections 16^a by which a temperature controlling medium, such as water, or steam, may be circulated through the support. The 30 latter is also provided with a flat top against which the scraper bar 19 rests throughout its length so that the temperature of the support is readily transmitted to the scraper.

In operation the knife, or scraper, is positioned with its edge 35^a directly in front 35 of the groove 7 at the front side of the supporting bar 6, as shown in Figs. 5, 6 and 7. By means of the screws 25 the scraper is moved inwardly and outwardly 40 at one, or both ends, and if need be, is sprung at the center by means of the tension bolts 31 and 32, and the bar 6 is also made perfectly straight by means of the bearing blocks 18, and the screws 12 and 45 14. The purpose of these adjustments, as it will be understood, is to provide two absolutely straight parallel opposing surfaces, one of which supports the web while the other determines the thickness of the coating 50 layer applied thereto. The web A, which is threaded between the scraper and the bar 6, receives an excess of the coating material from the roller 1, which is carried upwardly, as shown in Fig. 7, into contact 55 with the edge of the knife, or scraper, which distributes the coating evenly in a thin sheet.

In coating papers, especially with materials which contain substances of a granular, or crystalline nature, difficulty is experienced if it happens that these particles are not thoroughly dissolved, and also if dust, or other foreign particles of matter are carried in the coating solution, because, especially when the coating layer is thin, such

gritty particles will lodge in front of the scraper and cause the coating on the web to be marked with long streaks. Occasionally such a particle will perforate the web, or tear it severely. These disadvantages are 70 entirely overcome by my present arrangement of parts, because the support over which the web passes comprises the spaced shoulders *a* and *b*, which are so close together that the web lies flat between them, 75 but which are separated sufficiently to permit the web to be deflected, at any point between its extreme edges sufficiently to allow the undissolved granule of the coating material, or some foreign substance, such as a 80 piece of grit, to be carried around or beyond the edge of the scraper without either tearing the paper, or streaking the coating thereon.

I claim as my invention:

1. In a coating machine, the combination with a bar having a groove across which a web of paper to be coated passes, of a scraper arranged to coöperate with the web between the edges of the groove in said bar. 85 90

2. In a coating machine, the combination with a web supporting member having a bearing face against which the web to be coated bears, of a scraper positioned in front of the support and out of contact with the 95 face of the web thereon, said bearing face having a groove the edges of which sustain the web at each side of the working edge of the scraper and in proximity thereto.

3. In a coating machine, the combination with a bar having a curved face over which a web to be coated passes having a longitudinally extending channel across which the web travels, of a scraper opposing said channel having provision for one adjustment 100 105 transversely toward and from the bar and movable bodily into and out of operative position.

4. In a coating machine, the combination with a bar having a curved face over which a web to be coated passes having a longitudinally extending channel across which the web travels, of a scraper provided with a working edge facing said channel and having provision for a micrometer adjustment 110 115 relative to the bar and rotary movement to carry it bodily into and out of its adjusted position.

5. In a coating machine, the combination with a hollow bar having a narrow longitudinal groove in its face, of a scraper located in front of the bar having a narrow working edge positioned between the edges of the groove, a hollow support for the scraper, means for adjusting the latter and pipe connections for supplying a temperature controlling medium to said bar and support. 120 125

6. In a coating machine, the combination with a bar for supporting a web to be coated, of a scraper extending substantially at right 130

angles to the face of the bar, means on the scraper engaging the bar for effecting adjustment of one of said parts toward and from the other.

5 7. In a coating machine, the combination with a rigid support having a face over which a web to be coated passes, of a scraper

located in front of said face, adjusting devices for the ends of the scraper coöperating with the support and means carried by said scraper for independently adjusting the center thereof toward and from the face of the support.

JOHN G. JONES.
